COLLET CHUCK OR THE LIKE

James M. Kemper, Wilmington, Ohio

Application April 10, 1956, Serial No. 40,999

Term of patent 14 years

(Cl. D54—14)

Fig. 1

Fig. 2

Fig. 5

Fig. 4

Fig. 1 is a top perspective view of a collet chuck or the like, showing my new design.

Fig. 2 is a bottom perspective view of the device of Fig. 1.

Fig. 3 is an elevational view of the side of the device opposite the side illustrated in Fig. 1.

Fig. 4 is a bottom elevational view of the device of Fig. 1.

I claim:

The ornamental design for a collet chuck or the like, as shown.
